UNITED STATES PATENT OFFICE.

JAMES B. MEACHAM, OF BENNINGTON, VERMONT.

DESIGN FOR A DOOR-FASTENER.

SPECIFICATION forming part of **Design No. 32,122**, dated **January 23, 1900**.

Application filed December 14, 1899. Serial No. 740,359. Term of patent 14 years.

To all whom it may concern:

Be it known that I, JAMES B. MEACHAM, a citizen of the United States, residing at Bennington, in the county of Bennington and State of Vermont, have invented and produced a certain new and original Design for a Door-Fastener; and I do declare the following to be a full, clear, and exact description of the invention, such as will enable others skilled in the art to which it appertains to make and use the same.

The invention relates to a new and original design for a door-fastener; and it consists of a design of the shape and configuration shown in the accompanying drawings, in which—

Figure 1 is a perspective view. Fig. 2 is a side elevation.

The leading feature of the design com-

prises a loop-shaped portion 1, the part 2 of which is straight and projects over toward the 20 part 1 and is separated therefrom by a narrow space and thence extends downwardly at an- gle and is formed with a wedge-shaped out- wardly-projecting toe 3.

The device may be used as a window-fas- 25 tener or as a key-ring.

What I claim is—

The design for a door-fastener, as herein shown and described.

In testimony whereof I have hereunto set 30 my hand in presence of two subscribing wit- nesses.

JAMES B. MEACHAM.
